UNITED STATES PATENT OFFICE

GEORGE E. PICKUP, OF NEWARK, OHIO, ASSIGNOR TO THE WEHRLE COMPANY, OF
NEWARK, OHIO, A CORPORATION OF OHIO

DESIGN FOR A HANDLE FOR VALVES AND THE LIKE

Application filed July 21, 1930. Serial No. 36,420. Term of patent 7 years.

To all whom it may concern:

Be it known that I, GEORGE E. PICKUP, a citizen of the United States, residing at Newark, in the county of Licking and State of Ohio, have invented a new, original, and ornamental Design for a Handle for Valves and the like, of which the following is a specification, reference being had to the accompanying drawings, forming part thereof.

Fig. 1 of the drawings is a front elevational view of a valve handle showing my new design. Fig. 2 is a side elevational view of the same.

I claim:

The ornamental design for a handle for valves and the like, substantially as shown.

GEORGE E. PICKUP.
